UNITED STATES PATENT OFFICE.

HARRY S. WHEELER, OF ELIZABETH, NEW JERSEY, ASSIGNOR TO L. J. WING MFG. CO., OF NEW YORK, N. Y., A CORPORATION OF NEW YORK.

EXHAUSTER.

1,391,645.

Specification of Letters Patent. Patented Sept. 20, 1921.

Application filed May 8, 1920. Serial No. 379,882.

To all whom it may concern:

Be it known that I, HARRY S. WHEELER, a citizen of the United States, residing at Elizabeth, in the county of Union and State of New Jersey, have invented certain new and useful Improvements in Exhausters, fully described and represented in the following specification and the accompanying drawings, forming a part of the same.

10 This invention relates to exhausters, and has for an object to provide an improved device of this character in which the working parts are efficiently protected from contact with the gases which are drawn through the

15 machine.

Exhausters are commonly used to expel foul air, products of combustion, or other gases, which by reason of their heat or their chemical or other content have an injurious 20 effect upon the bearings or other working parts of the exhauster with which they come into contact. According to my invention, injury to the working parts of the exhauster is avoided by protecting them from the gases 25 exhausted by an envelop of constantly renewed air.

Further objects and advantages of my invention will be pointed out in connection with the detailed description of the specific 30 embodiment of the invention which is shown in the accompanying drawings, in which—

Figure 1 is a longitudinal, vertical section through the center of the exhauster;

Fig. 2 is an end elevation of the exhauster 35 with the fan removed; and

Fig. 3 is a fragmentary top view.

The frame work of the exhauster shown in the drawings consists of four longitudinal angle irons 1 connected at one end by horizontal and vertical angle irons 2 and 3, and at their other end by a frame 4 which constitutes the mouthpiece of the pipe or conduit 5 through which the gases to be exhausted are drawn. The pipe 5 is shown in 45 the form of an elbow rectangular in cross-section. The mouthpiece 4 is shaped at its inner end to correspond with the cross-section of the pipe 5 and is circular at its outer end.

50 Attached to projections 6 upon the inside of the mouthpiece 4 is a spider frame 7 whose inner portion is in the form of a ring 8. A tube 9 extends from an opening 10 in the rear wall of the pipe 5 to the ring 8.

55 A bearing casing 11 is adjustably mount-

ed in the ring 8 by means of the screw bolts 12, and in this casing is located the bearing 11' for the shaft 13. On the outer end of the shaft 13 is mounted a fan 14 of the propeller type operating to move the gases in a general axial direction, and the inner end of the shaft is coupled to the shaft of a motor 15 which is mounted upon a bracket 16 attached to the transverse angle iron 2 of the frame. The bearing 11 is lubricated from an oil cup 17 located at one side of the motor 15. An oil pipe leads from the oil cup 17 to the interior of the bearing casing 11. This pipe 18 lies within the tube 9.

The lower end of the pipe 5 is connected 70 by a pipe or suitable conduit with the chamber or receptacle from which foul air, or other gas, is to be exhausted.

When the exhauster is in operation, the rotation of the fan draws the gas to be exhausted through the pipe 5 and expels it through the mouthpiece 4. At the same time the fan draws air in through the opening 10 into the tube 9. This air passes around the bearing casing 11 and out between this casing and the ring 8, which forms the inner end of the tube 9. The air drawn in through the tube 9 thus forms an envelop about the bearing box 11 and the bearing 11', serving to cool the bearing and to protect it from contact with the gases exhausted through the pipe 5. Hot gases and gases containing active chemical elements or gases containing dust, grit, or other solid or liquid particles suspended therein may thus be drawn 90 through the exhauster without injury to its working parts.

The arrangement of the oil pipe 18 within the tube 9 prevents the gases exhausted through the pipe 5 from heating the oil 95 which passes through the pipe 18. The oil is thus brought to the bearing at a low temperature.

Another advantage of the embodiment of my invention which I have described is that 100 it provides a compact structure in which the motor is outside the path of the gases exhausted where it does not obstruct the flow of these gases. It is thus possible to use a smaller pipe and smaller fan than would be 105 possible were the motor within the pipe 5. Furthermore the motor is readily accessible.

My invention is by no means limited to the specific embodiment illustrated in the drawings. Thus the pipe 5 through which the 110

gases are exhausted may be circular in cross-section or of other desired form. This pipe need not form an elbow as is shown in the drawing, and it may, if desired, be provided 5 with a plurality of gas intakes instead of the single intake shown at the bottom in the drawings. A steam engine, internal combustion engine, or other rotor may be substituted for the electrical motor shown, or the 10 fan shaft may be driven by means of a belt pulley or other power connection.

The protective envelop of fresh air introduced through the tube 9 to protect the working parts from the gases exhausted may 15 be made use of in an exhauster in which the motor is placed within the pipe 5 directly behind the fan. In this case the air drawn in through the pipe 9 serves to cool the motor as well as the fan bearing, and to protect 20 the motor from the injurious action of chemicals or dust or grit carried by the gases exhausted.

What is claimed is:

1. An exhauster, comprising a pipe 25 through which the gases to be exhausted are drawn, a fan having a bearing located within said pipe and spaced inwardly from the wall of said pipe, a tube extending from said bearing to and through the wall of said pipe, 30 and means for rotating said fan to cause a suction through said pipe and through said tube.

2. An exhauster, comprising a pipe 35 through which the gases to be exhausted are drawn, a propeller fan mounted in said pipe with its axis extending longitudinally of the pipe, a tube extending from the rear of the central portion of said fan through the wall of said pipe, and means for rotating said fan 40 to cause a suction through said pipe and through said tube.

3. An exhauster, comprising a pipe 45 through which the gases to be exhausted are drawn, a tube extending into said pipe, a shaft extending through said tube, a bearing for said shaft at the inner end of said tube and in the path of the current of air drawn through said tube, a fan on said shaft, and means for rotating said shaft, whereby said

fan will cause a suction through said pipe 50 and through said tube.

4. An exhauster, comprising a pipe through which the gases to be exhausted are drawn, a fan in the mouth of said pipe mounted upon a shaft extending through the outer wall of said pipe, a motor without said pipe arranged to rotate said shaft, a tube extending into said pipe and surrounding said shaft, and a bearing for said shaft located at the inner end of said tube, whereby the 60 rotation of said fan will draw air through said tube and around said bearing, protecting it from the gases exhausted through said pipe.

5. An exhauster, comprising an elbow pipe 65 through which the gases to be exhausted are drawn, a shaft bearing within said pipe, a frame supporting said bearing and having an annular opening surrounding said bearing, a tube extending from said annular 70 opening through the rear wall of said elbow, a motor without said elbow, a shaft extending from said motor through said tube and mounted in said bearing, and a fan on said shaft adjacent to said bearing.

6. An exhauster, comprising a pipe 75 through which the gases to be exhausted are drawn, a fan, a bearing for said fan within said pipe, a tube extending from said bearing through the wall of said pipe, a lubricant receptacle without said pipe, and a lubricant pipe extending through said tube from said receptacle to said bearing.

7. An exhauster, comprising a pipe 80 through which the gases to be exhausted are drawn, a propeller fan for drawing the gases through said pipe, a bearing for said fan centrally located within said pipe, and means for providing a protective envelop of 85 constantly renewed air between said bearing and the gases exhausted through said pipe.

In testimony whereof I have hereunto set my hand in the presence of two subscribing witnesses.

HARRY S. WHEELER.
